BOTTLE CARRIER

Nicholas Snelling, Jackson Heights, Long Island, N. Y., assignor, by mesne assignments, to Zimba Beverage Co., Inc., New York, N. Y., a corporation of New York

Application August 4, 1938, Serial No. 223,039

1 Claim. (Cl. 224—45)

This invention relates to devices for carrying or supporting bottles of various kinds and classes, and particularly bottles having removable closure caps; and the object of the invention is to provide a supporting device of the character described made from heavy paper or light cardboard which is die cut, printed, lithographed, or otherwise characterized, and then folded to form a means for carrying, handling, or assembling bottled goods either individually or collectively so as to facilitate the handling and packaging as well as delivery thereof; a further object being to provide a device of the character described having an apertured portion from which or by means of which the device including the bottle or bottles thereon may be suspended or carried; a further object being to provide a device of the character described wherein a number of bottles may be collectively packed in a carton or shipping case with the carrying or suspending device attached thereto or to a number of bottles in a compact and collapsed manner and whereby the group of bottles may be simultaneously removed from the carton or shipping case in the removal of the supporting device therefrom, thereby simplifying the handling of merchandise of this kind by the merchant and also facilitating the packing and carrying thereof; a still further object being to provide an improved method of constructing a device of the character described so as to adapt the same for use in a continuous assemblage upon a multiplicity of bottles moved relatively thereto so as to expedite the assemblage of the device to groups of bottles, and further to incorporating a device of this character upon bottled goods in the operation of capping or sealing the same; and with these and other objects in view, the invention consists in a device of the class and for the purpose specified which is simple and economical in construction, and which may be produced and used in accordance with the method more fully hereinafter described and claimed.

The invention is fully disclosed in the following specification, of which the accompanying drawing forms a part, in which the separate parts of my improvement are designated by suitable reference characters in each of the views, and in which:

Fig. 1 is a perspective sectional view of a shipping box or case illustrating an arrangement of one of my improved supporting devices upon a number of bottles arranged therein with the device in collapsed position.

Fig. 2 is an end and sectional view through the

device shown in Fig. 1 illustrating the bottles removed from the carton or case with the parts in position as carried in the hand.

Fig. 3 is an enlarged sectional detail view of one of a number of sections of the supporting device shown in Figs. 1 and 2 and also illustrated in Figs. 5 and 7.

Fig. 4 is a plan view of a blank from which the device shown in Figs. 1 and 2 is formed.

10 Fig. 5 is a plan view of another form of blank which I employ.

Fig. 6 is a diagrammatic view illustrating the use of the device as seen in Fig. 5.

15 Fig. 7 is a diagrammatic plan view showing a method of applying a continuous supporting strip to two series of conveyed bottles prior to forming individual supporting sections or devices such as shown in Figs. 1, 2 and 4.

20 Fig. 8 is a diagrammatic view illustrating a modified form of construction which may be employed in a process similar to that illustrated in Fig. 7, but incorporating a different type of supporting strip or sheet; and,

Fig. 9 is a detail view of a part of the strip 25 employed in Fig. 8.

In Fig. 4 of the drawing I have shown a plan view of a blank from which a supporting device such as illustrated in Figs. 1 and 2 of the drawing is made. This blank, however, is similar to the blanks which will be made from the continuous sheet shown in Fig. 7 as later described. The blank consists of an oblong rectangular strip of material such as heavy paper or light cardboard. This strip or blank is scored to form 30 a central fold line 10 at opposite side walls of which are fold lines 11 dividing the central portion of the sheet into supporting sections 12, 12a; the latter having a supplemental fold line as at 11a to provide for the collapsing of the sections 12, 12a in the manner illustrated in Fig. 1. Outwardly of the fold lines 11 are other fold lines 13 which form bottle supporting flanges or flaps 14 and outer lock flanges 15. The parts or flanges 14 are provided with a series of semi-keyhole apertures 16 consisting of a small radius 17 and a larger radius 18; the latter forming an aperture sufficient to pass over the usual closure caps 19 such as Crown caps as applied to bottles 20 of various kinds, classes and description. The 40 diameter of the portion 17 conforms with the reduced neck 21 of the bottle 20 beneath the cap 19 as will appear in a consideration of the sectional view in Fig. 2 of the drawing.

45 The lock or retaining flanges 15 are provided with recesses opening outwardly through the

edges thereof having inner radii 22 corresponding to the radii 17 so that when the flap 15 is folded upon the under surface of the flanges or parts 14, the radii 22 of said recesses will register with the radii 17 of the apertures 16 to form a true circle. Thus wall structures are provided between both parts 14, 15, which entirely encircle the neck 21 of the bottle to form complete circumferential supports beneath the caps 19 preventing displacement of the bottles from the parts 14, 15, as will be apparent. The outer edges 15a of the part 15 extend beyond the center of the radii 22 so as to reinforce the mounting of the bottles in connection with the parts 14, 15, and also prevent accidental displacement of the lock flanges or flaps 15.

The part 12 is cut out to form a large elongated aperture 23 for receiving the fingers of a hand; whereas the other part is cut similarly along the lines 24, but the flap 25 is retained and folded on the line 26 so as to extend through the opening 23 in forming a reinforced finger grip as well as a non-cutting handle support for the device as will appear on a consideration of Fig. 2 of the drawing.

In coupling the carrying device shown in Fig. 4, with six bottles as at 20, it will be understood that the caps of the bottles are first passed through the large radius apertures 18. The flaps 14 are then moved across the bottles to bring the small radii 17 onto the necks 21 of the bottles below the caps after which the flanges or flaps 15 are simply folded downwardly and forced into position. This operation firmly moves the bottles or the necks of the bottles into the small radii 17 and thus the bottles are locked into position. When thus assembled, the six bottles may be carried collectively in the manner illustrated in Fig. 2 of the drawing and may be placed in a shipping case or carton such as indicated at 27 in Fig. 1 of the drawing with the supported bottles arranged in supporting compartments 28 formed between longitudinal partitions 29 and transverse partitions 30. It is understood that the mounting of the bottles in connection with the supporting device is such as to compensate for the partitions employed in the packing and shipping of the bottles. When arranged in the shipping case or carton, the parts 12, 12a are folded downwardly upon the top of the bottles as shown in Fig. 1. It will thus be seen that the device will not occupy any appreciable amount of space and thus the complete case may be shipped with the supporting or carrying device attached to each six bottles as is illustrated. In this way, the bottles may be collectively removed from the shipping case by the merchant in the sale thereof.

When the group of six bottles are carried, they will assume a position substantially similar to that illustrated in Fig. 2 as viewed from the end of the holder. No striking of the bottles will take place in that the bottles lean toward each other when carried. It will of course be understood that the holder may be constructed to support, two, four, or any series of bottles disposed at opposite sides of the holder. It is also possible to arrange one, two or three bottles on a holder which would consist of just one half of the complete devices illustrated in Fig. 4.

In Figs. 5 and 6 I have illustrated one other adaptation of the present invention which consists in providing an elongated narrow blank having score or fold lines 31 and 32 to divide the blank into a hanging or suspending end portion 33 having an elongated substantially keyhole

aperture 34 therein, an intermediate portion 35 having an aperture 36 similar to the apertures 16; that is to say, provided with a small radius end portion 37 and a larger radius end portion 38. At the other end of the blank is a locking flap or flange 39 having a recess in the outer edge thereof of a radius 40 which corresponds to the radius 37 to provide when the flap 39 is folded inwardly upon the lower surface of the part 35, a circular aperture as is clearly illustrated in Fig. 3, which will envelope the neck of the bottle 20a shown in Fig. 6 below the cap 19a thereon. This type of construction is adapted for suspending a sample bottle or a bottle to be delivered upon the knob 41 of a door 42 partially represented in Fig. 6. When the portion 33 is arranged upon the shank 41a of the knob, the bottle 21a will be supported substantially in the position illustrated in Fig. 6.

At this time it will be understood that bottles of various kinds and classes as well as various sizes may be merchandised and distributed or carried in the manner set forth. When small sample bottles are employed, the suspending or carrying means will be proportionately constructed. However, the invention lends itself effectively to the distribution and sale and carrying of such bottled goods as beer, and other alcoholic and non-alcoholic drinks usually sold in bottles, as well as in the sale of cream, milk, and many other types of drinks. It will also be understood that the invention is applicable for use in the sale and handling of other types of bottled goods especially when distributed as samples or when sold in groups of two or more. In all cases, the advertising or display matter may be directly applied to one or both surfaces of the device by printing, lithographing, or otherwise, as will be apparent.

In Fig. 7 of the drawing I have shown diagrammatically the method of continuously applying the holding or carrying device to a successive series of bottles in which event a long strip of cardboard or similar material 43 is provided having arranged thereon a successive series of apertures 16a, similar to the apertures 16, corresponding series of the recesses 22a, similar to the recesses 22, and apertures or cut outs 23a, 24a, similar to 23 and 24. The corresponding score or fold lines are shown in Fig. 7, as illustrated in Fig. 4 of the drawing, so that the resulting cut individual holders 43a, part of one of which is shown at the right of Fig. 7, will each be the same as the holder shown in Figs. 1, 2 and 4 of the drawing.

With the method shown in Fig. 7, two series of bottles 20b and 20c are fed through suitable conveyors and guides 44, 45, respectively beneath the continuous strip 43. Means will be provided for first moving the strip downwardly over the caps of the bottles. The side flanges or flaps as at 15b are then folded inwardly by suitable means, or by hand if desired, to lock the bottles in position upon the strip 43; and when in the locked position, suitable means will be provided to cut the strip as at 46 intermediate each three bottles 20b, 20c, so that the resulting severed groups will be the same as shown in Fig. 4. It will be understood in this connection that the design and arrangement of the strip 43 may be such as to provide a series of two or four bottles in this process by simply constructing and arranging the apertures 23a, 24a, to suit the particular cutting of the strip or grouping of the bottles which is desired. It will also be appar-

ent that the strip 43 in addition to being die cut and scored may also be printed or characterized prior to the coupling of the bottles therewith so that one continuous process will be provided.

In Figs. 8 and 9 of the drawing another adaptation is shown in which a continuous sheet 47 is employed which differs from the sheet 43 in that the flanges 15b are omitted and substituted for the apertures 16a are circular apertures 48. 10 Otherwise the strip or sheet 47 will be identical with the strip or sheet 43. In this process or continuous method of procedure, the strip 47 is arranged upon bottles 20d by first passing the necks 49 of the bottles through the apertures 48 and then afterwards applying the caps 50 to the bottles by suitable capping means as indicated diagrammatically by dot and dash lines at 51 in Fig. 8 of the drawing. In other words, the same effect can be produced by capping the bottles after the supporting sheet has been attached thereto. However, this process can be employed only where the application of closure caps or other covers can be applied in this manner. It will be apparent that certain merchandise requires capping and sealing under conditions which would not permit of the advanced mounting of the sheet 47 on the bottles. The method and procedure as disclosed diagrammatically in Fig. 7 would be applicable in most cases and could be 30 incorporated without material interference with present practices of handling bottled goods.

In connection with the process disclosed in Figs. 7 and 8, it will be apparent that the packing of bottled goods in shipping cartons is materially speeded up in that the group of bottles arranged in the holder may be simultaneously set or positioned in the carton or case which eliminates the handling of individual bottles.

It will also be apparent that in referring to 40 bottled goods, I have also had in mind products which are arranged in jars and similar containers; and in fact may be used in conjunction with any type of package goods, the package of which will facilitate the use of a holder of the kind under consideration.

It is obvious that cuts or perforated lines may be arranged in the flaps or flanges 15 intermediate the recesses 22 and extending to the fold line 13 to facilitate individual removal of the bottles at each side of the supporting device. If desired, the flap may be simply torn between 45 these recesses to accomplish the same result. It

will also appear that the so-called suspending portion in addition to forming a means for arranging advertising matter thereon, may also be in the form of a display tag, label, instruction or direction sheet, and need not necessarily be apertured. As a matter of fact, it is within the scope of my invention to incorporate a sheet of this type which may be of a different structure or texture than that employed in the foldably related parts coupled with and secured upon the bottle or other article. Still further, it will be apparent that the extending portion may form a means for supporting another article in connection therewith; and in like manner, another article may be supported in the device between the folds of the two parts 14 and 15. To illustrate the latter, it will be apparent that if the device is arranged upon a bottle of ink, a conventional fountain pen filling tube may be disposed within the folds of the parts 35, 39, which parts are of sufficient dimensions to adapt the device for such use.

Having fully described my invention what I claim as new and desire to secure by Letters Patent is:

A device for supporting an article having an enlarged and a restricted portion, said device comprising a blank cut and scored from sheet material to form a suspending part and an article-engaging part with a fold line therebetween, said article engaging part comprising one member extending integrally from the first part and foldable with respect thereto and a second member foldable under the first named member and integral with the end of the first named member, the free end of the second member being independent of said first named part, the first named member having a large article-receiving aperture adapted to pass over the enlarged portion of the article, the said aperture having a reduced side portion conforming with approximately one half of the circumference of the restricted part of the article to be engaged, and the second named member having a segmental notch engaging substantially the other half of the restricted part of said article and serving to force the article toward the reduced portion of the aperture of the first named member, the said reduced portion of the aperture and the said notch cooperating to encircle the restricted portion of the article beneath said enlarged portion in suspending an article from said first part.

NICHOLAS SNELLING.
